CLAIM

The ornamental design for a light fixture, as shown and described.

DESCRIPTION

FIG. 1 is a top perspective view of a light fixture showing my new design;

FIG. 2 is a side elevational view of the light fixture of FIG. 1;

FIG. 3 is a top view of the light fixture of FIG. 1; and,

FIG. 4 is a bottom plan view of the light fixture of FIG. 1.

The broken lines shown in the drawings represent environment and unclaimed portions of the design, and form no part of the claimed design.
